(57) **CLAIM**

What is claimed is the ornamental design for a breather device, as shown and described.

DESCRIPTION

FIG. 1 is a front, top raised perspective view of the breather device showing our new design.

FIG. 2 is a front, bottom lower perspective view of the breather device of FIG. 1.

FIG. 3 is a front side elevational view of the breather device of FIG. 1.

FIG. 4 is a back side elevational view of the breather device of FIG. 1.

FIG. 5 is a left elevational view of the breather device of FIG. 1.

FIG. 6 is a right elevational view of the breather device of FIG. 1.

FIG. 7 is a top plan view of the breather device of FIG. 1; and,

FIG. 8 is a bottom plan view of the breather device of FIG. 1.

The broken lines shown in the views depict environmental subject matter only and form no part of the claimed design.
